DESIGN FOR A LETTER OPENER OR SIMILAR ARTICLE

Max L. Goldbert, New York, N. Y.

Application May 2, 1945, Serial No. 119,364

Term of patent 14 years

(Cl. D74—1)

To all whom it may concern:

Be it known that I, Max L. Goldbert, a citizen of the United States and a resident of New York city, in the State of New York, have invented a new, original, and ornamental Design for Letter Opener or Similar Article, of which the following is a specification, reference being had to the accompanying drawing, forming a part thereof in which

Figure 1 is a face view of a letter opener or similar article, showing my new design.

Fig. 2 is a section on the line 2—2 of Fig. 1;
Fig. 3 is a section on the line 3—3 of Fig. 1.
The opposite side of the device from that shown in Figure 1 is plain.

I claim:

The ornamental design for a letter opener or similar article, as shown and described.

MAX L. GOLDBERT.
